MACHINE FOR DIE DRAWING METAL TUBES

Wallace E. Kerr, Youngstown, Ohio

Application August 10, 1949, Serial No. 109,451

11 Claims. (Cl. 205—7)

This invention relates generally to a machine for die drawing metal tubes and more particularly to such a machine incorporating novel means for receiving and aligning tubular workpieces with a drawing die.

The principal object of the invention is the provision of a machine for die drawing metal tubes incorporating relatively simple and efficient means for receiving and rectilinearly moving and positioning tubes in alignment with a drawing die.

A further object of the invention is the provision of a machine for die drawing metal tubes incorporating structure controllable from a single location and enabling the machine to be operated by one man.

A still further object of the invention is the provision of a machine for die drawing metal tubes wherein the mandrel and the tube receiving and aligning means is adjustable and controllable from one position thereby reducing the time heretofore believed necessary in the operation of comparable machines.

A still further object of the invention is the provision of a machine for die drawing metal tubes which incorporates a grip buggy and means for engaging a prime mover and controllable by the tension exerted on the said prime mover.

The machine for drawing metal tubes as disclosed herein will be recognized by those skilled in the art as a structure comparable in some respect with draw benches and similar apparatus heretofore known in the art in which a metal workpiece of a tubular nature is positioned over a mandrel and aligned mechanically with a die and moved therethrough for reducing the diameter of the tubular workpiece. Such machines for die drawing metal tubes have been heretofore constructed and used and in which a plurality of mandrels have been provided with means for feeding a tubular workpiece over one mandrel while another workpiece is being drawn through the die over another mandrel. Various mechanical constructions have been devised, built and used for moving the mandrel and tubular workpiece receiving means of the apparatus from tube receiving or loading position to drawing position.

The present invention resides primarily in the novel means for receiving such tubular workpieces and moving them rectilinearly and axially into substantial alignment with the drawing die whereby they may be engaged in the said die and the desired drawing operation performed.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side elevation of the machine for die draw-

2

ing metal tubes with parts broken away and parts in cross section.

Figure 2 is an end elevation taken on line 3—3 of Figure 1.

Figure 3 is a vertical section taken on line 4—4 of Figure 1.

Figure 4 is a top plan of the device in Figure 3.

Figure 5 is an enlarged vertical section taken on line 5—5 of Figure 1.

Figure 6 is an enlarged side elevation of a portion of the device illustrated in Figure 5.

Figure 7 is a plan view of a portion of the device illustrated in Figures 5 and 6.

Figure 8 is an enlarged detail of a portion of the device shown in Figure 1.

Figure 9 is an enlarged detail of a portion of one of the barrels illustrated in Figure 1.

Figure 10 is a side elevation of a sleeve wrench engageable in the end of the barrel illustrated in Figure 9 for adjusting the longitudinal position of the barrel in the apparatus.

Figure 11 is an end view taken on line 12—12 of Figure 6 and Figure 1.

Figure 12 is a cross section taken on line 13—13 of Figure 1.

By referring to the drawings and Figures 1 and 2 in particular it will be seen that a machine for die drawing metal tubes has been disclosed which comprises an assembly of devices for receiving tubes to be shaped, moving the tubes into approximate alignment with a die, positioning them in the die and drawing them through the die.

In Figure 1 of the drawings the tube feeding means is generally indicated by the letter F, the tube receiving and aligning means by the letter R and the forming die by the letter D. The means for gripping the tube and moving it through the die is generally indicated by the letter G.

In conjunction with these several main portions of the device an end abutment portion of the apparatus, generally indicated by the letter A, is movable longitudinally of the machine to move the tube receiving and aligning means into the die D so that the tube can be gripped by the gripping means G. It will thus be apparent to those skilled in the art that the machine for die drawing metal tubes disclosed herein comprises a plurality of inter-related co-ordinated devices for feeding a tube to be drawn into a suitable receiving section of the machine where it is positioned over a mandrel and then moved into substantial alignment with the drawing die. It is then presented to the drawing die by movement of the abutment end portion of the machine and gripped by the gripping means. Simultaneously with the initial drawing action of the gripping means, the mandrel is moved into the die area and the drawing process continues until the tube is moved completely out of the machine.

In describing the apparatus capable of accomplishing the operation automatically, rapidly and under the control of one operator, like numerals indicate like parts in the various views of the drawings. The drawings and description comprise a preferred embodiment of the invention.

Still referring to Figures 1 and 2 of the drawings it will be seen that a die stand 10 is positioned on one end of a draw bench 11 which in turn is supported by vertical supporting means 12 and which includes longitudinally extending tracks 13 on which a grip buggy 14 is reciprocally mounted. The grip buggy 14 includes jaws 15 for gripping a reduced end of a tubular member T. The grip buggy 14 includes a hook 16 engageable with a link chain 17 which in turn is carried over a plurality of sprockets 18 on the draw bench 11 and provided with means energizing the same so as to move the upper portion of the

link chain 17 which is engaged by the hook 16 to the right, as illustrated in Figure 1 of the drawings.

Means for feeding tubes T to the die D on the die stand 10 and for engagement by the jaws 15 of the grip buggy 14 comprise an elevated tube supporting stand S and a pair of pinch rolls 19 by means of which tubes T positioned on the elevated tube supporting stand S may be moved longitudinally of the machine, to the left as shown in Figure 1 of the drawings. The tube receiving and aligning means, generally indicated by the letter R, comprise a plurality of tube receiving barrels 20, each group of which is mounted on at least two pairs of double acting elevators 21-21 and 22-22. The double acting elevators 21-21 are located adjacent the die stand 10 and the elevators 22-22 are located adjacent the outer end of the device and spaced with respect to the die stand 10 by a longitudinally extending I beam 23. The two pairs of elevators 21-21 and 22-22 are each inter-connected by means of tubular guides 24 as well as by the plurality of barrels 20 heretofore described. The elevators 21-21 are shown in greater detail in end, side and top plan views in Figures 5, 6 and 7 of the drawings.

The elevators 22-22 are shown in end and top plan elevations in Figures 3 and 4 of the drawings, and by referring thereto it will be observed that they incorporate means for moving the barrels 20 rectilinearly as well as means for controlling the longitudinal movement of the barrels 20 when in axial alignment with the die D and during a drawing operation. It will be observed that the means for moving the barrels 20 rectilinearly from tube receiving to die aligning position are identical in both of the pairs of elevators 21-21 and 22-22. Longitudinally extending shafts 25 and 26 are positioned through the stands 27 and 28 supporting the elevators 21-21 and 22-22. Crank arms 29 and 30 connect the elevators 21-21 with the shafts 25 and 26 and secondary crank arms 31 and 32 connect the shafts 25 and 26 to the means limiting the longitudinal movement of the barrels 20-20 as hereinafter described in detail.

The elevators 21-21 are actuated by vertically positioned elevator shafts 33 and 34, as best seen by referring to Figures 5 and 6 of the drawings. The shafts 33 and 34 being positioned for vertical movement in two pairs of supporting brackets 35-35 and 36-36 which are in turn secured to the elevator stand 27. Each of the elevator shafts 33 and 34 is connected at its lowermost end with the outermost end of the arms 29 and 30 by means of links 37 and 38, respectively. Means for moving the elevator shafts 33 and 34 vertically are provided and comprise pneumatic piston and cylinder assemblies 39 and 40, the piston rods of each being indicated by the numerals 41 and 42. It will be observed that the piston rod 41 is pivoted at its outermost end to the arm 29 and the piston rod 42 is pivoted at its outermost end to the arm 30. The cylinders 39 and 40 are pivoted at their opposite (upper) ends as by pivots 43 and 44 to the brackets 35 and 36. Means is provided for the pneumatic actuation of the piston and cylinder assemblies 39 and 40 as will be understood by those skilled in the art.

It will be obvious that the motion imparted to the arms 29 and 30 by the piston and cylinder assemblies 39 and 40 will be conveyed by the longitudinally extending shafts 25 and 26 to the elevator supporting stand 28 and more particularly to the arms 31 and 32 therein which actuate the longitudinal movement limiting means and the secondary elevators 22-22 which are connected at their lowermost ends by means of arms 45 and 46 with the shafts 26 and 25, respectively. The secondary elevators 22-22 include vertical shafts 47 and 48 which correspond with the vertical shafts 33 and 34, heretofore referred to in connection with the elevators 21-21.

By referring to Figure 1 of the drawings it will be observed that the I beam 23 which extends between the elevator stand 27 and the secondary elevator stand 28 has a pair of tandem connected piston and cylinder assemblies

49 and 50 mounted thereunder. The cylinder of the piston and cylinder assembly 50 is fixed to the I beam 23 and the cylinder of the piston and cylinder assembly 49 is slidably mounted for longitudinal movement with respect to the I beam 23. The piston of the piston and cylinder assembly 50 is connected to the cylinder of the piston and cylinder assembly 49 so that the latter may be moved thereby. The piston of the piston and cylinder assembly 49 has a piston rod 51 which is connected through a suitable connection 52 with a drive shaft 53 which in turn extends rearwardly and is journaled in a ball bushing 54 on an end abutment stand 55. A pair of similarly formed and oppositely disposed rocker arms 56 and 57, as best illustrated in Figure 2 of the drawings, are mounted on the drive shaft 53 for longitudinal movement with respect to the device and for pivotal movement on the drive shaft 53, as shown in dotted lines in Figure 2 of the drawings.

By referring to Figure 1 of the drawings it will be observed that the extreme outer ends of the tubular guides 24-24 are secured to connecting members 58-58 which in turn are positioned for vertical movement on vertical guide bars 59-59 which are integral parts of the rocker arms 56 and 57. It will thus be seen that the tube receiving barrels 20-20 are supported above the I beam 23 and parallel therewith by the elevators 21-21 and 22-22 and connected to the rocker arms 56 and 57 by the tubular guides 24-24. It will also be seen that in order to move the barrels 20-20 from tube receiving to tube feeding position with respect to the die D in the die stand 10, the operation of the elevators 21-21 and 22-22 and the rocker arms 56 and 57 is necessary as the barrels 20-20 are in end alignment therewith in tube receiving and tube feeding positions and move in a rectilinear pattern between these respective positions.

In operating the device, a tube T is positioned on the stand S from whence it may be fed by the pinch rolls 19 into one of the barrels 20-20 which is supported in elevated relation to the die stand 10, as shown in Figure 1 of the drawings, by the elevators 21-21 and 22-22. Air pressure is introduced into the piston and cylinder assembly 49 which moves the drive shaft 53 longitudinally of the device and away from the area of the die stand 10 and thereby moves the rocker arms 56 and 57 away from the die stand 10 (to the left as shown in the drawings), which action moves the barrels 20-20 away from the tube receiving and feeding position and at the same time causes them to swing outwardly on arcs based on the vertical shafts 33 and 34 and 47 and 48, respectively, as these shafts are fixed with respect to horizontal movement by their connections to the elevator stands 27 and 28. This action is best illustrated in Figures 4 and 7 of the drawings and by referring thereto it will be seen that dotted lines indicate the arcuate patterns followed by each of the elevators 21-21 and 22-22 as they are moved on a horizontal plane by the aforesaid longitudinal movement of the rocker arms 56 and 57. When the elevators 21-21 and 22-22 have moved to horizontally and vertically spaced position, as shown by dotted lines in Figures 4 and 7, as occasioned by the rearward movement of the rocker arms 56, the rocker arms 56 and 57 will each be inclined from vertical, as shown in dotted lines in Figure 2 of the drawings.

It will thus occur to those skilled in the art that the respective barrels 20-20 will have moved rearwardly with respect to the die stand 10 and horizontally on the arcs illustrated in Figures 4 and 7 of the drawings so that the elevators 21-21 and 22-22 are spaced horizontally with respect to one another as well as vertically. When this has occurred, the connection 52 on the drive shaft 53 will engage a valve 60 which will permit the energization of the pneumatic piston and cylinder assemblies 39 and 40 which are then actuated to move the vertical elevator shafts 33 and 34 and 47 and 48 so that the uppermost assembly of barrels 20-20 move downwardly and

the lowermost assembly of barrels 20-20 move upwardly. Thus, a tube T positioned in one of the barrels 20-20 of the uppermost assembly is moved downwardly to the horizontal plane of the die D on the die stand 10. When this occurs, the piston and cylinder assembly 49 is energized and the rocker arms 56 and 57 are moved thereby inwardly toward the die stand 10 (to the right in the drawing), which action swings the elevators 21-21 and 22-22 to the position illustrated in solid lines in Figures 4 and 7 of the drawings wherein the barrels 20-20 are again located on the same vertical plane and the lowermost assembly has moved into horizontal and vertical alignment with the die D on the die stand 10. Such action automatically moves the end of the tube T into the die D and partially therethrough in which position the previously reduced end of the tube T may be gripped by the jaws 15 of the grip buggy 14 for a subsequent drawing action.

It will occur to those skilled in the art that it is necessary to position a mandrel within the area of the die D in order to control the wall thickness and interior diameter of the tube T being drawn. Mandrels M are accordingly carried on the outermost ends of mandrel rods 61 which are positioned in each of the barrels 20-20 and over one of which the tube T had previously been positioned when it was placed in one of the barrels 20. In order that the tube T may be easily moved into the die D, the barrel 20, the mandrel M and the rod 61 on which it is secured are held in retracted position while the tube T is moved into drawing position with respect to the die D by the pneumatic piston and cylinder assembly 50 which is energized for this purpose and exerts its motion through the pneumatic piston and cylinder assembly 49, the drive shaft 53 and the rocker arms 56 and 57 as heretofore described. This latter action occurs when the jaws 15 of the grip buggy 14 have engaged upon the tube T and have begun to move it through the die D. Thus, the initial effort of moving the tube is reduced by this delayed positioning of the mandrel M. A suitable grip buggy construction and driving chain arrangement is illustrated and described in my Patent No. 2,404,234, issued July 16, 1946, on Drawing Machine.

In order that the mandrel positioning operation just described may be automatically performed, a valve 62 is positioned adjacent the link chain 17 for operation by a vertical cone-shaped plunger 63 (see Figure 1), the upper end of which is adapted to be engaged by the chain 17 when the same is in slack position and the valve 62 thereby held in closed position. When the hook 16 of the buggy 14 engages the link chain 17 and tension is exerted on the chain, the same will rise upwardly and assume the position of the lines of force between the hook 16 and the outermost sprocket (not shown) which will lift the chain 17 with respect to the plunger 63 and thereby permit the valve 62 to open. The valve 62 controls the piston and cylinder assembly 50 which is then energized and moves the rocker arms 56 and 57, the barrels 20-20 and, most importantly, the mandrels M into proper position so that the proper automatic sequence of operation is mechanically achieved. It will be observed that during this operation the elevators 21-21 and 22-22 are in stationary position as the barrels 20-20 are movable longitudinally with respect thereto as are the mandrels M on their mandrel rods 61.

Means for adjusting the effective location of the barrels 20-20 and the mandrel rods 61 and hence the positioning of the mandrels M with respect to the die are provided and comprise the formation of the feeding ends 20A of each of the barrels 20-20 in a hollow hexagon shape, as best shown in Figure 9 of the drawings, so that the same may be rotated by the application of a sleeve-like wrench 64, as shown in Figure 10, and which wrench includes a ratchet mechanism 65 and an extending handle 66. The wrench 64 is positioned over one of the mandrel rods 61 and used in rotating the barrel 20 in which it is

positioned and which barrel is threadably engaged in one of the elevators 22-22 and thereby capable of longitudinal movement. As shown in Figures 3 and 4 of the drawings, the elevator 22 has a threaded bore 22d and the tube receiving barrel 20 has an exteriorly threaded portion 20e engaging the threaded bore 22d of the elevator 22.

In order that the operation of the elevators 21-21 and 22-22 may be more readily understood, the same are illustrated in detail in Figures 3, 4, 5, 6 and 7. By referring now to Figures 3 and 4 of the drawings it will be seen that the stand 28 which supports the elevators 22-22 also carries two pairs of oppositely disposed, horizontally extending brackets 67 and 68 which have journals formed on their outermost ends for slidably receiving the vertical elevator shafts 47 and 48 which carry the elevators 22-22 on their uppermost ends. The elevators 22-22 are more particularly described as comprising rotatable body members 69 and 70 located on the uppermost ends of the vertical shafts 47 and 48 and each of which has a sidewardly extending arm 71 and 72, the outermost ends of which carry bushings 73 and 74 which in turn rotatably support the elevators 22-22, as heretofore described.

Each of the elevators 22-22 comprises in effect a body member partially supporting one group of barrels 20-20, as heretofore described, and one of the guide rods 24. Each group of barrels 20-20 and guide rod 24, which interconnect each of the elevators 21-21 and 22-22, respectively, thus hold the same in horizontal spaced alignment with one another and it will be understood that there are two elevator assemblies 22 on the elevator stand 28, two elevator assemblies 21 on the elevator stand 27, and two groups of barrels 20-20.

Still referring to Figures 3 and 4 of the drawings, it will be observed that the upper portion of the elevator stand 28 forms a platform 75 having upstanding guides 76 at both sides thereof and vertically movable abutments 77 inwardly from the sides thereof. These vertically movable abutments 77 are pivotally connected to the arms 31 and 32, heretofore described as being connected to the longitudinally extending actuating shafts 25 and 26, by way of links 78 and 79, respectively. The vertically movable abutments 77 are automatically positioned by the actuation of the shafts 26 and 25 and prevent longitudinal movement of the barrels 20-20 and their mandrels M toward the die D during the tube drawing operation, and automatically reverse their effective and retracted positions in accordance with the vertical movement of the vertical elevator shafts 47 and 48, so as to properly register with the elevator 22 adjacent thereto.

By referring now to Figure 4 of the drawings it will be observed that the elevators 22-22 move into position adjacent the abutments 77 when in their lower tube feeding position, as previously described, and that they are each provided with flat elongated abutting surfaces so that their alignment with the abutment members 77 on the upper end of the elevator stand 28 is automatically maintained. As heretofore described, the elevators 22-22 are provided with threaded bores through which the barrels 20-20 are positioned for adjustment longitudinally with respect to the apparatus so that the positioning of the mandrels M, which are carried one in each of the barrels 20-20, may be varied with respect to the die D in the die stand 10. It will also be seen that the mandrel rods 61-61 are detachably connected to the outermost ends of the barrels 20-20 at points 20B so that they may be removed and replaced, as desired.

By referring now to Figures 5, 6 and 7 of the drawings, detailed illustrations of the elevator stand 27 may be seen and it will be observed that each of the elevators 21-21, respectively, carried thereby are connected to the guide rods 24 and the barrels 20-20 in substantially the same manner as the elevators 22-22, heretofore described. Each of the elevators 21-21 is supported

on a bushing 80 which is in turn carried on the outermost ends of arms 81 and 82 which have body members 83 and 84 rotatably positioned on the uppermost ends of the vertical elevator shafts 33 and 34. It will thus be seen that the longitudinal alignment of the barrels 20-20 and the guide rods 24-24 always maintain the proper transverse positioning of the elevators 21-21 despite their rectilinear movement as occasioned by the vertical movement of the shafts 33 and 34 and the transverse arcuate movement of the arms 81 and 82 as heretofore described.

Still referring to Figures 5, 6 and 7 of the drawings it will be obvious to those skilled in the art that once the rocker arms 56 and 57 have moved outwardly with respect to the die stand 10, the pneumatic piston and cylinder assemblies 39 and 40 may be individually or simultaneously energized, as desired.

In Figures 6 and 11 of the drawings, alternating valves 85 are illustrated for effecting the automatic alternating action of the piston and cylinder assemblies 39 and 40 and it will be observed by referring thereto that they are operated by arms 86 carried on the ends of the shafts 25 and 26 and where they extend through the elevator stand 27. The alternating valves 85 control the air supply to the piston and cylinder assemblies 39 and 40 and with respect to a main air supply line 87 and by way of a control valve 88. The control valve 88 is a four-way valve which controls the action of the elevators 21-21 and 22-22 by way of the pneumatic piston and cylinder assemblies 39 and 40 heretofore described so that desired sequence of operation may be obtained.

It will be obvious to those skilled in the art that a suitable source of air pressure is in communication with the main supply line 87 and that suitable piping (not shown) connects the supply line 87 with the valve 62, which is operated by the position of the main driving chain 17, and the piston and cylinder assembly 50, controlled thereby. The various valves employed, other than those heretofore mentioned, are not further described or illustrated herein, as they are commercial devices and known in the art.

It will thus be seen that the device disclosed herein possesses certain features not found in the apparatus heretofore known in the art and particularly in the construction and operation of the elevator mechanism by means of which the barrel and mandrel tube receiving portions of the device are alternately positioned in tube receiving and tube feeding position and moved rectilinearly between these positions by the simple expedient of endwise movement of the tube receiving barrel and mandrel assemblies themselves as occasioned by their slideable and pivotal connections with the sidewardly movable and longitudinally movable rocker arms 56 and 57. Thus, the pneumatic piston and cylinder assemblies 49 and 50 and the piston and cylinder assemblies 39 and 40 are able to effectively move the tube receiving barrels 20-20 from tube receiving position horizontally, vertically and again horizontally, in a rectilinear pattern to the end that a simple and efficient mechanism is provided which may be economically constructed and easily and efficiently operated as compared with the apparatus heretofore known in the art for achieving this purpose and such as, for example, that disclosed in the previously issued U. S. Patents No. 2,196,155 to H. W. Smith and No. 2,472,231 to W. Rodder.

Having thus described my invention, what I claim is:

1. In a machine for die drawing metal tubes, pipes and the like the combination of a die, a pair of mandrel rods and a pair of tubular barrels positioned over said rods, rocker arms for holding said mandrel rods and tubular barrels in position relative to said die and for moving the same toward and away therefrom, elevator means for simultaneously lowering one of the said mandrel rods and tubular barrels in a rectilinear path out of loading position

into drawing position and elevating the other of the said mandrel rods and tubular barrels in an oppositely rectilinear path from substantially the same drawing position into substantially the same loading position, the said tubular barrel and mandrel comprising means for supporting a tube, the said rocker arms movable longitudinally of the said machine for engaging the said tube and mandrel in the said die.

2. In a machine for die drawing metal tubes a die, a pair of tube receiving barrels each having a mandrel rod therein, and means for movably supporting the said tube receiving barrels and mandrel rods comprising elevator stands incorporating spaced vertically movable shafts having inturned arms pivoted thereto and carrying the said barrels and mandrel rods on their outermost ends, pivoted rocker arms movable longitudinally of said machine and connected to said barrels and mandrel rods for moving said barrels and mandrel rods longitudinally and transversely on arcs based on said shafts, and means for alternately raising and lowering the said shafts to move said barrels and mandrel rods bodily rectilinearly in oppositely disposed paths toward and away from said die.

3. Apparatus according to claim 2 further characterized by the said barrels and mandrel rods being adjustable longitudinally with respect to said inturned arms and the said die.

4. In a machine for die drawing metal tubes including a stationary die and a bench extending forwardly therefrom; a forward moving means, at a place on and extending forwardly along said bench, for applying a moving force; a device movable along said bench for drawing the tube through said die, a coupling element secured to said device at a point spaced from said means, said element being operative to couple said device to said means whereby application of said moving force to said point displaces said means from said place; a retractile mandrel mounted rearwardly of and for forward movement to within said die, a motor for so moving said mandrel, a follower biased to bear on said means and so displaceable therewith, a controller for said motor actuated by the displacement of said follower whereby application of said moving force effects said forward movement of said mandrel to within said die.

5. In a machine for die drawing metal tubes, a die, a pair of rods having secured respectively thereto mandrels for alternate insertion within the tubes within the die, a pair of rod holding members respectively anchoring the rod ends remote from said mandrels, rectilinearly guided elevators on opposite sides of the machine for respectively supporting said members for alternate movement along a plane into and from a position in a plane in axial alignment with said die, means to alternately effect the ascent and descent of said elevators; a second means for moving the said members and rods, anchored respectively thereto, along the second said plane into axial alignment with and alternately toward and away from said die, a pair of retractile abutments and linkages respectively associated therewith and with the first said means for moving the elevators, so transmitting movement from the descent of the latter to retract one retractile abutment for one said member out of the second said plane and the ascent of the other said member to advance the other retractile abutment for the other said member into said plane.

6. A machine for die drawing metal tubes including a die, longitudinally positioned tube holding means, means for sustaining said tube holding means in position for the reception of a tube, said last mentioned means including transversely positioned arms, supports for said arms on which the same are pivotally mounted for horizontal swinging movement to move said tube holding means bodily laterally along a horizontal plane to a position axially out of alignment with said tube receiving position, said supports being movable vertically to effect movement of said tube holding means along a plane normal to the first mentioned horizontal plane to a position axially out of

alignment with said die, said arms being movable to move said tube holding means from said last mentioned position along a plane parallel to said first mentioned horizontal plane of movement of the tube holding means to a position in axial alignment with said die, means to effect said horizontal swinging movements of said arms, and means to effect vertical movement of said supports on which said arms are mounted.

7. In a machine for die drawing metal tubes, a stationary die, a tube holding means including a tube receiving barrel for sustaining a tube in axial alignment with said die, an elevator carrying said tube holding means, a mandrel insertable within a tube for location within said die and spaced therefrom by the tube, a rod secured to said mandrel and extending within said tube and barrel and anchored to the latter at a point remote from the mandrel, said barrel having a screw threaded portion rotatable within and axially located by said elevator, whereby rotation of said barrel effects axial adjustment of said mandrel with respect to said die.

8. A manipulator for feeding attenuated articles from an elevated retracted position to a lowered advanced position comprising, a plurality of pairs of bearings in spaced relation lengthwise of an article, each bearing providing vertical guide means, a vertical shaft for each guide means, mounted therein for straight line vertical movement between the aforesaid elevated and lowered position, a transverse arm mounted on each of said shafts, for oscillation about the shaft as an axis between said retracted and forward position, the arms of one pair extending to- 30

ward the arms of the other pair in overlapping relation, article holding means supported by the arms of each pair and means for actuating said shafts and arms for alternate operation so that as the shafts of one pair are lowered, the shafts of the other pair are raised while the arms are oscillated out of overlapping relation, to and from the aforesaid positions.

9. A manipulator as in claim 8, wherein said arms are provided with a screw threaded bore and said article holding means has a screw threaded portion received in said bore for rotary adjustment.

10. A manipulator as in claim 8, in which said means for actuating said arms comprises actuating arms mounted for longitudinal movement and for oscillation, a connection between each of said actuating arms and each one of the arms of each pair of transverse arms, and means for actuating said actuating arms.

11. A manipulator as in claim 8, and in which said article holding means are pivotally supported by the 20 transverse arms.
